SIGNALING DEVICE

Harry W. Seiger, Los Angeles, Calif.

Application September 26, 1936, Serial No. 102,726

4 Claims. (Cl. 128—138)

This invention relates generally to alarm systems, and more particularly to an electrical device for use in signaling the wetting of a bed or bed clothes by the occupant thereof.

5 An object of the invention is to provide a device which, in its association with an infant in its crib, activates a suitable visual or audible signal when the infant urinates, so as to enable the infant's diaper to be changed immediately in 10 order to avoid prolonged exposure of the infant to a cold wet diaper, with the attendant danger of contracting bronchopneumonia, which is the chief cause of high mortality in infants under eight months of age. The reduction in diaper 15 rashes and irritations, due to prolonged contact of the infant's delicate skin with its urine, is another direct benefit resulting from use of the device.

Another object of the invention is to provide a 20 wet diaper signaling device which is structurally characterized to enable its use without discomfort to the infant and in entire safety from electrical shock or injury, while insuring that the signal will be activated upon the closing of a 25 circuit by the electrolytic action of salts in the infant's urine forming a current conducting bridge between normally insulated conductors embedded in the device.

A further object of the invention is to provide 30 a signaling device characterized by its structural simplicity and sanitary features, requiring no replacement of any circuit controlling element or substance rendered inactive and unfit for further use by urine, as embodied in devices heretofore 35 proposed.

With these and other objects in view, the invention consists in the following combinations and arrangements of elements as set forth in the following specification and particularly pointed 40 out in the appended claims.

In the accompanying drawing,

Figure 1 is a plan view of the invention;

Figure 2 is a longitudinal sectional view taken on the line 2—2 of Figure 1;

45 Figure 3 is a diagrammatic view illustrating a preferred form of electrical circuit embodied in the invention;

Figure 4 is a plan view of a modified form of the invention.

50 Referring specifically to the drawing and particularly to Figures 1 to 3, inclusive, the invention comprises a relatively thin and flexible pad 10 of soft material such as elastic rubber having high electrical insulating properties. The pad 55 is rectangular in outline and its marginal edge

is beveled as indicated at 11 so as to avoid any shoulder or corner which might cause discomfort to an infant when the pad is disposed beneath the diapered portion of the infant lying in its crib.

5 Embedded in one side of the pad and bonded thereto so as to be exposed and flush with the top surface of the pad, are contact elements C and C' constructed from thin and flexible sheet metal to provide rectilinear bars 12 and 12a from which project at a right angle and in 10 opposite directions fingers 13 and 13a. The fingers of the respective bars are alternately arranged in parallelism so as to interfit in sufficiently spaced relationship to be normally insulated electrically from each other by the pad, all 15 as clearly shown in Figure 1.

Conductor wires 14 and 15 are embedded in the pad and are connected to the respective bars 12 and 12a. These wires extend through a flat handle 16 formed integrally with the pad at one 20 end thereof, and are included in a relay circuit with a local battery 17 of 4½ or 6 volts, and the winding of a relay 18.

The fixed contact 19 of the relay forms part of 25 an alarm circuit including the battery 17, a signal 20 which may be audible or visual and the relay armature 21 which is associated with the relay winding to close the alarm circuit when the winding is energized by closing of the relay circuit, all as clearly shown in Figure 3. A main 30 switch 22 is included in the relay circuit to control the latter.

The operation of the invention is as follows:

With the signal 20 located at a suitable place to be seen or heard by one in attendance to an 35 infant, and with the pad 10 disposed beneath the diapered portion of the infant when lying in its crib, it will be clear that when the infant urinates, the wet diaper will form a current conducting bridge across one or more of the fingers 40 13 and 13a to electrically connect the contact elements C and C', thus closing the relay circuit, it being assumed, of course, that the main switch 22 is closed.

As the relay 18 is now energized, the alarm 45 circuit will be closed through the relay switch formed by the contact 19 and armature 21, so as to activate the signal 20 and thus indicate that the infant's diaper should be changed. The main switch 22 can be opened should circumstances prevent the immediate changing of the diaper, so as to prevent continued activation of the signal. It will be appreciated that the alarm circuit can be provided with a domestic source of current supply and a suitable step-down trans- 55

former (not shown) in order to avoid a large drain of current upon the local battery 11.

Should the diaper be changed immediately, it is, of course, not necessary to open the main switch 5 22, as the relay circuit will be broken upon removal of the wet diaper from the pad. The device requires no adjustment or handling to render it ready for re-use, and it is not necessary that the pad be dried or wiped off after each operation. The pad can be washed occasionally to maintain it in a proper sanitary condition, but other than this operation, the device requires no servicing. The flow of current in the relay circuit by the closing thereof as a result of the electrolytic action of salts in the infant's urine is so small as to be incapable of causing any sensation to the infant even though its bare buttocks were to rest directly on the contact elements. Thus no harm to the infant would result from the use of 10 20 the device, and the flexible pad would cause no discomfort.

The form of device shown in Figure 4 operates upon the same principle as the form just described and differs structurally therefrom by the provision of a circular or ovate pad 10a in the top surface of which are embedded so as to be exposed and flush therewith, contact elements C2 and C3. The elements are in the form of flexible wires spirally arranged alternately in sufficiently spaced relation for their adjacent convolutions to be normally insulated electrically from each other by the pad. As the operation of this form of the invention is identical to that of the form previously described, further description is deemed 30 35 unnecessary.

It will be appreciated that it is not necessary to use a wet diaper to create an electrical bridge between the contact elements on the pad 10, but that any absorbent material wet with urine or 40 even a sufficiently thick film of urine alone will act as the electrical bridge across the contact elements. Thus with a pad of a larger size, the device can be used as a signal by adults with mental disorders, motor and sensory paralysis

around the bladder area, or any form of involuntary emptying of the bladder.

What is claimed is:

1. In a signaling device of the class described, a thin pad of soft rubber which is non-absorbent to aqueous solutions and which is adapted to be disposed beneath the diapered portion of an infant in its crib; and contact elements embedded in the pad to be exposed from and flush with a surface of the pad in sufficiently spaced relationship 10 to be normally insulated electrically from each other by the pad, yet be electrically bridged by urine wetting the infant's diaper.

2. In a signaling device of the class described, a pad of insulating material which is non-absorbent to aqueous solutions; and flexible contact elements embedded in the pad and composed of a multiplicity of portions distributed over the area of the pad embedded therein and exposed from one surface thereof in sufficiently spaced 15 20 relationship to be normally insulated electrically from each other by the pad but which are adapted to be bridged by an electrolyte.

3. In a signaling device of the class described, a pad composed of an integral body of flexible 25 and electrically insulating material which is non-absorbent to aqueous solutions, and flexible contact elements of current conducting material having portions embedded in and exposed from one surface of the pad and spaced apart so as to be 30 35 electrically insulated from each other but which will be bridged by an electrolyte.

4. In a signaling device of the class described, a pad of insulating material which is non-absorbent to aqueous solutions, contact elements 40 embedded in the pad and exposed from one face thereof and substantially flush with a surface of the pad, said contact elements being spaced sufficiently from each other to be normally insulated electrically from each other by the material in the pad, said contacts adapted to be bridged by an electrolyte.

HARRY W. SEIGER.
